UNITED STATES PATENT OFFICE.

JOHN J. GARRETT, OF TRUMANN, ARKANSAS, ASSIGNOR OF TWO-FIFTHS TO MARTIN
McGRATH, OF TRUMANN, ARKANSAS.

HOLDER FOR HATS, COATS, UMBRELLAS, &c.

1,208,767.

Specification of Letters Patent. Patented Dec. 19, 1916.

Application filed January 6, 1916. Serial No. 70,663.

To all whom it may concern:

Be it known that I, JOHN J. GARRETT, a citizen of the United States, residing at Trumann, in the county of Poinsett and 5 State of Arkansas, have invented a new and useful Holder for Hats, Coats, Umbrellas, &c., of which the following is a specification.

This invention relates to a holder for coats, hats, umbrellas and the like, one of 10 the objects of the invention being to provide a coin controlled lock by means of which the several articles placed on the holder will be securely fastened in position so that they cannot be removed by unauthorized persons.

15 A further object is to provide a device of this character which is simple and durable in construction, attractive in appearance, and which can be operated readily to fasten the articles in position.

20 With the foregoing and other objects in view which will appear as the description proceeds, the invention resides in the combination and arrangement of parts and in the details of construction hereinafter described and claimed, it being understood that 25 changes in the precise embodiment of the invention herein disclosed, can be made within the scope of what is claimed, without departing from the spirit of the invention.

30 In the accompanying drawings the preferred form of the invention has been shown.

In said drawings:—Figure 1 is a front elevation of the holder, the parts being 35 shown in active positions. Fig. 2 is an elevation of one side of the structure. Fig. 3 is an elevation of the opposite side of said structure. Fig. 4 is a top plan view. Fig. 5 is a side elevation, the parts of the holder 40 being shown in their open or normal positions. Fig. 6 is an enlarged vertical transverse section through the casing of the lock and showing the relative positions of the parts while an article is secured to the 45 holder. Fig. 7 is a view similar to Fig. 6, but showing the relative positions of the parts when unlocked by the insertion of a coin. Fig. 8 is an enlarged section on line A—B Fig. 6, the position of a key in the 50 lock being indicated by dotted lines.

Referring to the figures by characters of reference 1 designates a back board or base preferably extended vertically and adapted to be secured to a wall or other structure. 55 Extending from this base is a pair of hooks

2 and 3 arranged one above the other and pivotally connected to the base as at 4 is a retaining member 5 having an opening 6 from which extends a slot 7. Opening 6 is bridged by arcuate guard wires 8 preferably crossed as shown, while the slot 7 is also bridged by crossed arcuate wires 9 or the like. It will be noted that the free end portion of the retaining member 5 is arched, as at 10, the slot 7 extending from the opening 6 to the space under this arch. 60

A series of retaining loops 11 is provided upon the base 1, there being a supporting ledge 12 or the like below the lowermost loop and which is adapted to support a cane, umbrella or the like inserted down through the loops 11. A guard plate 13 extends laterally from the retaining member 5 and is adapted, when said member is in active position, to extend directly over the series of loops 11, 70 as shown particularly in Figs. 1, 2 and 3.

It will be understood that the parts herein-before described can be used efficiently as a means for holding a hat, coat, and umbrella or the like, by placing the hat on the upper 80 hook 2, hanging the coat upon the lower hook 3, and inserting the umbrella or cane downwardly through the loops 11 until it rests on the support 12. The retaining member 5 is then swung downwardly to the position shown in Figs. 1, 2 and 3, so that the crown portion of the hat will be received in the opening 6 and will be guarded by the arcuate wires 8, while that portion of the coat engaging the hook will be received in 90 the slot 7 and held on the hook by the guard wires 9 and by the arch 10. Plate 13 will assume a position above the upper end of the cane or umbrella, thus preventing the upward removal thereof from the loops 11. 95

For the purpose of fastening the retaining member 5 in active position, a novel form of locking means has been provided. It will be noted that an arcuate link 14 is pivotally connected to ears 15 outstanding from the base 1, this link having a longitudinal slot 16 in which is slidably mounted a stud 17 extending laterally from the retaining member 5. A connecting rod 18 is pivotally attached at one end to the link 14 and at its other end to a slide 19 mounted on the base and the lower end portion of which extends into a lock casing 20. That portion of the slide within the lock casing is formed with ratchet teeth 21 adapted to 105 110

be engaged by a pawl 22 which is held in engaging position by a spring 23. The pawl and the ratchet teeth coöperate to prevent upward movement of the slide. The pawl 5 22 has a transverse recess 24 normally interposed between a key receiving slot 25 in the front face of casing 20 and a recess 26 in the base 1. Recess 26 is adapted to receive a stud 27 at the end of a key indicated 10 generally at 28, a portion of this key being adapted to enter the recess 24 in the pawl so that when the key is rotated the pawl will be retracted against the action of its spring 23 and out of engagement with the 15 toothed slide 21.

For the purpose of preventing the key from turning under certain conditions, a channel 29 has been provided in the casing 1 and slidably mounted in this channel is a bar 30 having a wing or projection 31 adapted to be limited in its sliding movement by stops 32 in the casing. A guard 33 extends across the bar and serves to hold it against lateral displacement. Under normal conditions, the projection 31 is adapted to contact with one side of the inserted key, thus to hold the key against rotation within the casing. A trip lever 33' is pivotally connected to the lower end of the bar 30 and 25 has a weight 34 thereon. One end of this lever projects into a coin chute 35 extending downwardly within the casing 1 from a coin slot 36, the lower portion of the coin chute discharging into a suitable coin receptacle, not shown. The downward movement of the lever within the coin chute is limited 30 by a stop 36' and in order that a deposited coin may be retained in the chute, a yieldingly mounted coin support 37 extends into the lower portion of the coin chute and is 35 engaged by one end of a crank shaft 38 journaled within suitable bearings 39 within the casing. An extension 40 projects from the shaft 38 and is adapted to be engaged by a spring finger 41 carried by the lower portion 40 of the slide 19. This finger is adapted to slide upwardly past the extension 40 during the upward movement of the slide 19 but will, during the downward movement of 45 the slide, engage the end portion of the extension 40 and press it downwardly thus to rotate the shaft 38.

As hereinbefore pointed out, under normal conditions the retaining member 5 is 50 swung outwardly as shown in Fig. 5. A hat can then be placed on the hook 2, a coat can be hung from the hook 3, and a cane or umbrella can be inserted through the loops 55 11 so as to rest on the support 12. The 60 parts of the lock will at this time be positioned as shown in Fig. 7. When the parts are in this position, the key in the lock will be held against rotation by the projection 31. The retaining member 5 is then swung 65 downwardly so that the crown portion of

the hat will enter the opening 6, while the hook 3 and the garment supported thereby will be received in the slot 7 and under the arch 10. Plate 13 will, as before described, prevent the upward withdrawal of the umbrella or cane from the loops 11. During this movement of the retaining member 5 to active position, slide 19 will move downwardly, the teeth thereon slipping past the pawl 22 so that after the parts have thus 70 been adjusted, it is impossible to raise the retaining member 5 to the position shown in Fig. 5 without first operating the lock mechanism. Although the key is held against rotation, it can be withdrawn by the person 75 using the device.

When it is desired to remove the articles secured in position, a coin of the proper denomination should first be inserted into the chute 35. This coin will fall upon that portion of lever 33 in the path thereof and will come to a stop upon the upper end of the member 37. The downward movement of lever 33' under the action of the coin will result in the upward movement of bar 30, 80 thus bringing the projection 31 out of the path of movement of the key. The key can then be inserted into the lock and rotated. This operation will disengage the pawl 22 from the teeth 21 and the retaining member 5 can thus be swung upwardly so as to release the engaged articles on the hooks. When the structure is again used the downward movement of the retaining member 5 will cause the descending finger 41 to engage the arm or projection 40 and rotate the shaft 38, with the result that the coin supporting member 37 will be moved downwardly and the coin thereon will thus be released and fall into a receptacle provided 85 for it. As soon as lever 33 is thus relieved of the weight of the coin, the weight 34 will return the lever to its initial position, 90 whereupon the mechanism will be reset.

What is claimed is:—

1. The combination with a base, outstanding garment engaging means thereon, and a retaining member hingedly connected to the base and having an opening for the reception of portions of the supported garments, of guards bridging the opening, means upon the base for receiving and supporting a cane or the like insertible downwardly thereinto, means upon the retaining member for preventing upward withdrawal of said cane or the like from the engaging means, and means for locking the retaining member in holding position.

2. The combination with a base and superposed garment engaging means outstanding therefrom, of a retaining member hingedly connected to the base and having an enlarged hat receiving opening into which one of the garment engaging means projects, arcuate guards bridging said open- 125

ing, said member having an outwardly bowed portion at the free end thereof for straddling a portion of a garment engaging the other garment engaging means, superposed cane receiving loops outstanding from the base, a guard plate extending laterally from the hinged retaining member and adapted, when said member is in retaining position, to overhang an object engaging the loops, means for locking the retaining member in garment holding position, 5 superposed cane receiving loops outstanding from the base, a guard plate extending laterally from the hinged retaining member and adapted, when said member is in retaining position, to overhang an object engaging the loops, and means for locking the retaining member in garment holding position.

3. The combination with a base and superposed garment engaging means outstanding therefrom, of a retaining member 15 hingedly connected to the base and having an enlarged hat receiving opening into which one of the garment engaging means projects, arcuate guards bridging said opening, said member having an outwardly bowed portion at the free end thereof for straddling a portion of a garment engaging 20 the other garment engaging means, super-

posed cane receiving loops outstanding from the base, a guard plate extending laterally from the hinged retaining member and 25 adapted, when said member is in retaining position, to overhang an object engaging the loops, means for locking the retaining member in garment holding position, said means including a slide, means on the base 30 for engaging the slide, means for transmitting motion from the retaining member to the slide when said member is swung into or out of retaining position, and locking means for engaging the slide to hold it 35 against movement.

In testimony that I claim the foregoing as my own, I have hereto affixed my signature in the presence of two witnesses.

JOHN J. GARRETT.
